MICRO-PROJECTOR

Ray P. Porter, Abilene, Tex.

Application January 9, 1933, Serial No. 650,875

10 Claims. (Cl. 88—24)

This invention relates to an improved illuminated micro-projector and seeks, among other objects, to provide a device of this character which will, with a small light source, effectually project 5 the image of a specimen so that it may be readily observed by several persons at one time.

Another object of the invention is to provide an illuminated micro-projector wherein lenses are employed which will permit the disposing of the 10 specimen near the light source and which will magnify the light beams in such a manner that the image of the specimen will be clearly shown within a dark box disposed below the lenses.

Another object of the invention is to provide an 15 illuminated micro-projector which is adapted to be adjustably carried on a stand and wherein the lenses and light source employed are adjustable with respect to the specimen stage so that the lenses may be focused for clearly projecting specimens of different types.

Another object of the invention is to provide a 20 micro-projector employing a light source of great simplicity and flexibility.

A further object of the invention is to provide 25 an illuminated micro-projector which is characterized by the utmost simplicity and compactness and which may be produced cheaply and on a large scale so that a class could be provided with individual instruments if desired.

And a still further object of the invention is 30 to provide a micro-projector employing a light source which will be so disposed that heating of the specimen will not occur.

Other and incidental objects of the invention, 35 not particularly mentioned in the foregoing, will be apparent during the course of the following description.

In the accompanying drawings forming a part 40 of this application,

Figure 1 is a perspective view of the device in 45 operative position,

Figure 2 is an enlarged fragmentary vertical 50 sectional view of the device,

Figure 3 is an enlarged fragmentary horizontal 55 sectional view on the line 3—3 of Figure 2, looking in the direction indicated by the arrows,

Figure 4 is an enlarged vertical sectional view 60 of the dark box employed, and

Figure 5 is an enlarged fragmentary vertical 65 sectional view showing a slightly modified form of illuminator.

Referring now to the accompanying drawings, 70 the numeral 1 indicates an upright stand which is similar in construction to the usual ring stands 75 commonly used in laboratories for supporting dif-

ferent implements used in experimental work. Associated with the stand is a straight supporting arm 2 which is externally threaded at its outer end and is provided with a double laboratory clamp 3 which is slideable on the stand 1. Screwed through the wall of the clamp 3 is a locking screw 4 which is adapted for locking the clamp and arm in a desired adjusted position on the stand.

Associated with the arm 2 is a stage 5 which is preferably formed of lightweight metal and is 10 square in shape. As best seen in Figure 3 of the drawings, the externally threaded outer end portion of the arm 2 is screwed into a side wall of the stage, medially thereof, and formed in the stage 5, centrally thereof, is an opening 6. Normally 15 overlying the opening is a removable object or specimen slide 7. Mounted on the stage 5, near one edge thereof, are spaced posts 8, and carried on said posts are spring fingers 9 which normally engage the slide 7 and retain it in a fixed position 20 over the opening.

Upstanding from the stage 5, at one corner thereof and near one of the posts 8, is an adjustable bracket supporting rod 10, and carried by said rod, at its upper end, is a flat metal bracket 11 which extends horizontally in parallel spaced relation to the stage thereabove. The bracket is widened towards its free end. Formed in the stage 5, near the rod 10, is a socket 12 and carried in the socket is a locking sleeve 13 which is 30 reduced and threaded at its outer end. Screwed on the threaded outer end of the sleeve 13 is a locking nut 14. As best seen in Figure 3 of the drawings, the socket 12 communicates with the opening through which the rod 10 passes and the 35 sleeve 13 is notched to receive the rod so that, when the locking nut 14 is rotated, the sleeve 13 is shifted outwardly for wedging the rod in locked position. It will be seen that the rod 10 may thus be locked in any desired position. 40

Carried on the bracket 11 at its enlarged outer end is the illuminator. The illuminator comprises a tubular sleeve 15 which extends through the enlarged outer end portion of the bracket 11 axially thereof. The major portion of the 45 tubular sleeve 15 extends above the bracket 11 and a small portion thereof extends below said bracket. Carried on the upper face of the bracket 11, in concentric spaced relation to the tubular sleeve 15, is a threaded socket 16 which is 50 adapted to receive the lower end portion of a conventional flash light barrel in a manner to be hereinafter described. Slidably fitted about the tubular sleeve 15 is a tubular housing 17 which is closed at its upper end by an end wall 18

preferably formed of insulating material. The housing is adapted to slide vertically upon the sleeve 15 and is rotatable thereabout for permitting adjustment, as will be hereinafter described in more detail. The end wall 18 is held in place by punching the upper rib of the wall of the housing inwardly into contact with the edge of the wall 18. Formed in the wall of the housing 17 is an opening 19 and formed in the wall 18 are spaced openings 20 for providing ventilation for the interior of the housing. Mounted concentrically within the housing 17, near its upper end, is a socket 21 which may be of the well-known bayonet type. The socket is held in place by set screws 22, preferably three in number, which are screwed through the wall of the housing 17 at equally spaced points thereon. Carried on the end wall 18 is a binding post 23 which is preferably electrically connected with the center terminal of the socket 21. A second binding post 24 is carried on the end wall 18 and is electrically connected with the rim terminal of the socket 21. Carried in the socket 21 is a bulb 25.

25 The binding posts are preferably electrically connected with a current source through a suitable switch so that the current to the bulb may be readily controlled. It should be understood that the screws 22 permit adjustment of the socket and bulb within the housing 17.

Snugly but slidably fitted within the tubular sleeve 15 is a condenser assembly which comprises, respectively, slidable inner and outer sleeves 26 and 27. The sleeve 26 is internally threaded at its lower end and screwed into said sleeve is a relatively large condenser lens 28. The sleeve 27 is provided with an enlarged portion 29 defining a shoulder 30 against which the upper end of the sleeve 26 abuts. The portion 40 29 is internally threaded and screwed therein is a rim 31 carrying a relatively small condenser lens 32. It is to be noted that the lens 28 is of substantially twice the diameter of the lens 32. The lens 32 should be of relatively short focal 45 distance so that it may be disposed in relatively close spaced relation to the bulb 25. The condenser lens 28 is so disposed that it will permit the placing of the bulb 25 near the lens 32 so that the transmitted divergent rays will be collected and converged upon the specimen, as will be more fully described hereinafter. It should be understood that the condenser lenses may be adjusted with respect to each other by simply 50 sliding the inner sleeve 26 within the outer sleeve 27. A more coarse adjustment may be obtained by sliding the entire condenser assembly within the tubular sleeve 15 and, of course, further adjustment may be accomplished by sliding the housing 17 upon the sleeve 15.

60 Mounted at a corner of the stage 5, substantially in alignment with the posts 8 and the rod 10, is a depending adjustable supporting rod 33 and associated with the rod 33 at its lower end is an objective supporting bracket 34. Associated 65 with the rod 33 is a locking sleeve 35 and a locking screw 36, the sleeve and screw 35 and 36 operating in a manner identical with the sleeve 13 and screw 14 previously described. As best seen in Figure 1, the objective supporting bracket 70 34 is preferably formed of flat metal and extends diagonally at right angles to the bracket 11 in horizontal spaced relation below the stage 5. Carried on the bracket 34, at its outer end, is an adjustable objective 37 which is preferably screwed into said bracket. Carried within the objective

37 are objective lenses 38 which are adjustable within the casing for varying the focus of light projected from the condenser lenses 28 and 32 through the specimen on the slide 7. The rod 33 is, of course, adjustable, as previously stated, for giving a coarse adjustment whereas the objective is adjustable for giving a very fine adjustment. The same condition applies to the rod 10 which may be coarsely adjusted and the condenser lens 28 which may be adjusted to a very fine point for projecting the desired amount of light through the specimen.

Associated with the stage and lenses is a preferably square dark box 39 and formed on the box 39, substantially medially of the top wall 15 thereof, is a preferably frusto-conical sight tube 40 which is normally disposed beneath the objective casing. Formed in the top wall of the box, near one side thereof, is a preferably triangular sight opening 41. As best seen in Figure 4 of the drawings, the dark box 39 is provided with a swinging front wall 42 which is hingedly connected to the box by means of hinges 43, the front wall 42 being raised when it is desired to insert the hand and remove or change the position of a drawing carried within the box.

In use, after a specimen slide containing a specimen to be observed has been placed over the opening 6, the bulb is illuminated. The student or professor desiring to observe the specimen 30 then adjusts the position of the condenser lenses and the objective lenses so that the beam of light from the bulb will be directed through the specimen and into the dark box, wherein the image of the specimen will be clearly shown upon a 35 sheet of paper or the like so that a drawing may be made of the specimen if desired. Attention is particularly directed to the fact that, inasmuch as a small condenser lens with a very short focal distance is employed, together with a second condenser lens, the small condenser lens may be placed very near the bulb so that the bulb will be disposed inside the focal point whereby the collection of the transmitted divergent rays may be converged to project through the specimen to 45 the objective lens. In this manner, it is possible to get sufficient illumination from a small flash light bulb to serve the purpose of micro-projection. This construction is particularly advantageous for the reason that it is possible to provide a very simple and compact lightweight micro-projector which may be readily adjusted.

Attention is further directed to the fact that heating of the specimen, which is sometimes caused by disposing the specimen too close to the light source, will be prevented in the present device for the reason that the condenser lenses permit the focusing of the light rays in such a manner that while the light source is disposed in distal relation to the specimen, diminishing of 60 the light is not caused. It is pointed out that the light source is so small that heat caused by said light source will not be present to any appreciable extent, in any event.

Attention is further directed to the fact that, 65 in view of the extreme simplicity of the device and the small number of working parts, it is possible to produce the device on a large scale so that individual instruments may be furnished members of a class at a small cost. The simplicity in construction, coupled with the ready adjustability of the various parts, permits the condenser and objective lenses to be quickly adjusted with respect to the specimen so that a number of specimens may be observed in quick 75

sequence without taking much time to adjust the device to suit the different specimens.

Referring now to the modified form of illuminator as shown in Figure 5 of the drawings, the numeral 44 indicates a bracket which is identical in construction to the bracket 11 and on which is mounted a sleeve 45 which is of like construction to the sleeve 15. Mounted in the sleeve 45 are the condenser lenses 46 which are similar to the lenses 28 and 32 of the preferred form. Mounted on the upper face of the bracket 44 is a socket 47 having an upstanding internally threaded flange 48, which socket is similar in construction to the socket 16. Screwed into the flange 48 is a tubular flash light barrel 49 which may be of any standard construction and is adapted to carry a bulb 50 which is disposed above the condenser lenses 46 in relatively close spaced relation thereto. The barrel 49 will, of course, carry the usual flash light batteries and will also be provided with a switch of conventional construction so that the bulb may be illuminated when desired. Aside from the above-discussed modified construction of the illuminator, the invention will function in a like manner to the preferred form in every respect.

It should be further noted that, if desired, the arm 2 may be rotated axially in the clamp 3 to a horizontal position for projecting the image against a vertical surface instead of a horizontal surface, as shown in the drawings.

It is to be understood that the lenses employed may be of any well-known commercial variety and may be bought separately and installed in the sleeves, if desired. It is to be further understood that the objective may be of a standard type, if desired.

It is, of course, obvious that the dark box described may be substituted by another type of dark box, or may be eliminated entirely, at the option of the operator.

It is believed that I have provided a simple, compact and lightweight micro-projector which may be utilized with the utmost facility in experimental and other work.

Having thus described the invention, I claim:

1. A micro-projector including a stage, mounting means therefor, a specimen slide carried on the stage, a condenser mounted above the stage, an objective mounted beneath the stage, illuminating means mounted above the condenser, and a dark box mounted beneath the objective and having a sight opening and a hinged front wall, said illuminating means cooperating with the condenser and objective for projecting the image of the specimen on the slide into the dark box and said hinged front wall being adapted to permit insertion of the hands whereby tracing of the image seen through the sight opening may be effected.

2. A micro-projector including a stage, adjustable mounting means therefor, a condenser mounted above the stage and supported thereby, illuminating means mounted above the condenser, an objective mounted below the stage, and a dark box mounted below the objective, said stage, condenser and objective being adjustable to different heights above the dark box and said illuminating means cooperating with the condenser and the objective for projecting the image of a specimen carried on the stage into the dark box.

3. A micro-projector including a stage, supporting means therefor, a rod carried at one end of the stage, a bracket carried by the rod above the stage, a sleeve carried by the bracket, inner

and outer sleeves carried within said first-mentioned sleeve, condenser lenses slidably mounted within the inner and outer sleeves, said inner and outer sleeves being slidable with respect to each other, illuminating means mounted above the condenser lenses, an objective carried below the stage, and means for adjusting the objective below the stage, said objective, condenser lenses and illuminating means cooperating for projecting the image of a specimen on the stage to a point 10 below the objective. 5

4. A micro-projector including a stage, supporting means therefor, a rod carried at one corner of the stage, a bracket carried by the rod above the stage, condenser lenses carried by the bracket, illuminating means carried by the bracket above the condenser lenses, a second rod carried by the stage at another corner thereof, and an objective carried by said second rod beneath the stage and cooperating with the condenser lenses 20 and the illuminating means for projecting the image of a specimen carried on the stage to a point beneath the objective.

5. A micro-projector including a stage, a supporting arm carried thereby, a stand associated 25 with the arm, condenser lenses carried above the stage, mounting means for said lenses, illuminating means carried by said mounting means above said lenses, an objective carried below the stage, and a dark box mounted below the objective in 30 spaced relation thereto, said objective, condenser lenses and illuminating means cooperating to project the image of a specimen carried on the stage to a point within the dark box.

6. A micro-projector including a stage, a specimen slide carried thereon, condenser lenses mounted above the stage, an objective mounted below the stage, illuminating means mounted above the condenser lenses, and a dark box mounted below the objective and provided with a 40 frusto-conical sight tube, the condenser lenses, illuminating means and objective being adjustable with respect to each other and to the dark box and cooperating to project the image of a specimen on the slide into the dark box through 45 the sight tube.

7. A micro-projector including a stage, a rod carried at one corner thereof, an objective supporting bracket carried by the rod below the stage, an objective adjustable in said bracket and 50 including a pair of objective lenses, condenser lenses mounted above the stage, an illuminator mounted above the condenser lenses, said condenser lenses being adjustable with respect to the illuminator and the stage, and a specimen slide 55 carried on the stage, said condenser lenses, illuminator and adjustable objective cooperating to permit the projection of the image of the specimen carried on the slide to a point below the objective. 60

8. A micro-projector including a stage, a rod carried at one corner thereof, a bracket carried by the rod above the stage, a sleeve carried by the bracket, an outer sleeve slidably within the bracket and having a relatively small condenser 65 lens, an inner sleeve carried within said outer sleeve and having a relatively large condenser lens, said inner and outer sleeves being slidable with respect to each other for varying the focus of the lenses, an illuminator carried by the bracket about said first-mentioned sleeve and comprising a housing and a socket and bulb within the housing, and an objective carried below the stage and cooperating with the condenser lenses and illuminator for projecting the image of a speci- 70 75

men carried on the stage to a point beneath the objective.

9. A micro-projector including a stage, an objective below the stage, condenser lenses above the stage, a bracket above the stage, condenser lenses carried by the bracket, a housing removably carried by the bracket above the lenses and having an opening, an insulating wall closing the upper end of the housing, terminals carried on said wall for connection to a current source, a socket within the housing, means concentrically mounting the socket within the housing, and a bulb carried in the socket and energizable by the current source, the bulb cooperating with the lenses and objective for projecting the image of a

specimen on the stage to a point below the objective.

10. A micro-projector including a stage, supporting means therefor, a condenser mounted above the stage and supported thereby, an objective mounted below the stage and supported thereby, illuminating means carried above the condenser, and a dark box carried beneath the objective, said illuminating means, said condenser and objective being independently movable with respect to each other and the dark box and co-operating for projecting the image of a specimen on the stage into the dark box.

RAY P. PORTER. 15
